UNITED STATES PATENT OFFICE.

WILLIAM EXHALL TEMPEST BENNETT, OF LONDON, ENGLAND.

HAND CONTINUOUS SELF-INKING ROLLING, MARKING, OR IMPRESSING MACHINE.

SPECIFICATION forming part of Letters Patent No. 469,668, dated February 23, 1892.

Application filed January 27, 1891. Serial No. 379,314. (No model.) Patented in England December 27, 1889, No. 20,799.

To all whom it may concern:

Be it known that I, WILLIAM EXHALL TEMPEST BENNETT, engineer, of 21 Warwick Road, Earl's Court, London, in the county of Middlesex, England, have invented a new or Improved Hand Continuous Self-Inking Rolling, Marking, or Impressing Machine, (for which I have obtained British Letters Patent No. 20,799, dated December 27, 1889,) of which the following is a specification.

My invention, which relates to a new or improved hand continuous self-inking rolling, marking, or impressing machine, has for its object to print, mark, or impress letters, figures, marks, lines, or any kind of devices on paper, parchment, cloth or fabric, or surface. Thus it may be used, among other purposes, for printing handbills, tickets, coupons, for obliterating postage-labels, for marking the names of places and dates thereon or on other papers or documents, for impressing facsimile signatures on letters and other documents, for printing any number of words, letters, figures, designs, drawings, or other marks in a particular order, and for ruling lines and spaces.

The machine consists of an impressing-roller carrying the types or designs to be printed and a roller for supplying ink to the said impressing-roller, an ink-containing chamber, from which the ink can be supplied to the inking-roller, as described, and a handle by which the apparatus is held while in use, and which can also be used for ejecting the ink.

I will describe the apparatus with reference to the accompanying drawings, in which—

Figures 1 and 2 are views at right angles to each other. Fig. 3 is a vertical section. Fig. 4 is a transverse section on the line 1 2, Fig. 1. Fig. 5 is a part vertical section at right angles to the section, Fig. 3. Fig. 6 is a longitudinal section of the impressing-roller. Figs. 7 and 8 are respectively a transverse section and an end view thereof, and Fig. 9 is a part end view opposite to that shown in Fig. 2. Fig. 10 is a sectional detail view showing the manner in which the piston is located or arranged within the reservoir, so as to be prevented from turning when the regulating-screw is turned for pressing ink into the trough from the reservoir.

The printing, marking, or impressing roller is marked A, and the roller which distributes the ink or other marking material onto the printing, marking, or impression roller is marked B. The body of the roller A, which may be of metal, wood, or other suitable material, is provided with slots, holes, or recesses *a* for the reception of the type or other printing, marking, or impressing pieces or devices *b*, as shown in Figs. 1 and 3, the said pieces or devices being fixed in position by a ring *a*², pressed against the printing devices by screws *a*³ in such a manner as to be capable of being removed and replaced by other pieces or devices when required. The printing or marking roller A and inking-roller B are mounted so as to revolve parallel to and in close contact with each other in a frame C, provided with a handle D. The inking-roller may consist of a cylinder or roller of thin metal or other material covered with cloth, felt, rubber, or other suitable yielding material *b*². Ink or other marking material is supplied to the surfaces of the covering *b*² from a trough F, supplied with ink from a reservoir G in the stem of the handle D, the ink being transferred from the roller B onto the type or other marking devices carried by the roller A continuously when the machine is in use. The rollers A and B are geared together, as shown at *c*, so that when the roller A is rotated the roller B will receive a positive rotation by the gearing and ink the surface of the printing or marking devices. The part D of the handle, which may be of wood, is fitted to the stem *c*², (constituting the ink-reservoir,) so as to be capable of being rotated thereon, and is provided with a block *e*, preferably of metal, having a hole or recess *f* to receive the square or equivalently-shaped end *g* of a screwed spindle *h*, which passes longitudinally through the stem *c*² and has a bearing in a plate or bar *i* in the top of the frame C. The part D of the handle is connected with the stem *c*² by the collar *o*, which is in two or more pieces or segments, and is fixed to the handle D by two or more screws *p p*. The collar is therefore removable at pleasure, and the reservoir or chamber G may be cleaned as desired. The block *e* is provided with a screw *s*, by which it is fixed to the handle D, and

is further held by the pins *t t*, that traverse the handle *D*, and screws *s* at right angles to each other.

Fitted to slide up and down in the ink-reservoir *G* is a piston *E*, provided with an internal screw-thread in which the screw *h* works, so that by turning the screw in one direction the piston (which is prevented from turning with the screw by any suitable means) will be caused to descend, and thereby force ink from the reservoir through the trough *F*, formed in the upper part of the frame *C*, and through a slot or a number of minute holes or slots *l* in the bottom of the trough onto the covering *b²* of the inking-roller *B*, and, conversely, by turning the handle *D* in the opposite direction, the piston *E* will ascend and the pressure on the ink or marking material be relieved. The distance between the axles of the two rollers *A* and *B* can be regulated, as required, by means of screws *m*.

A hole *n* is provided in the end of the trough *F*, through which hole the reservoir may be charged with marking material or the trough be cleaned out, the said hole being closed by a screw-plug when the machine is in use.

The perforations *l l* may be provided with a covering or slide pierced with holes or slots corresponding to those in the bottom of the trough *F*, and arranged in such a manner that when moved in one direction the slots or holes in it will coincide with those in the bottom of the trough *F*, and thus allow the ink or marking material to escape onto the inking-roller *B*. With such an arrangement of covering or slide the piston *E* could be forced down by a spring instead of by hand, as described.

To print or mark with this machine, all that is necessary after charging the reservoir *G* with ink or marking material is simply to roll or propel the roller *A* over and in contact with that part of the material to be marked or impressed with the markers or devices carried by the roller, the number of impressions that can be obtained being limited only by the numbers of revolutions of the impressing-roller.

I claim—
1. In a hand printing or marking machine, the combination of a rotating or movable

handle, a screw-spindle operated by said handle, an ink-reservoir, a movable piston, a trough communicating with said reservoir and supplying ink to the inking-roller, the printing and inking roller geared together so that when the printing-roller is moved by contact with the surface to be printed the inking-roller will be caused to move or rotate, and means for adjusting or regulating the distance between said rollers, substantially as shown, and for the purpose described.

2. In a hand printing or marking machine, the combination of the rotating or movable handle, the hollow stem thereof constituting an ink-reservoir, the block and collar detachably connecting said handle and stem, a screw-spindle vertically operated by said handle, a movable piston, a detachable frame provided with a trough which communicates with the reservoir, and an inking and marking roller supported or held in said frame, substantially as described.

3. In a hand printing or marking machine, the combination of the movable handle, the hollow stem constituting the ink-reservoir, the block and collar detachably connecting said handle and stem, a screw-spindle working in the reservoir and operated by the handle, a movable piston, a detachable frame connecting to the lower end of the stem and formed with a trough which communicates with the reservoir, an inking and printing roller supported in said frame, and means for adjusting the pressure of one of said rollers against or upon the other, substantially as described.

4. In hand-printing machines, the combination of a printing-roller, an inking-roller, a handle provided with an ink-reservoir, and a piston operated by said handle to force ink from said reservoir onto the said inking-roller, substantially as described.

In testimony whereof I have signed my name to this specification in the presence of two subscribing witnesses.

WILLIAM EXHALL TEMPEST BENNETT.
